UNITED STATES PATENT OFFICE

151,120

DESIGN FOR A FISHING REEL

Louis S. Elsinger, Tampa, Fla.

Application December 3, 1945, Serial No. 124,295

Term of patent 3½ years

(Cl. D31—4)

To all whom it may concern:

Be it known that I, Louis S. Elsinger, a citizen of the United States of America, residing at Tampa, in the county of Hillsborough and State of Florida, have invented a new, original, and ornamental Design for a Fishing Reel, of which the following is a specification, reference being had to the accompanying drawing, forming a part thereof.

In the drawing:

Figure 1 is a perspective view from the rear and one side of a fishing reel, showing my new design.

Figure 2 is a side elevation;

Figure 3 is a bottom plan view; and

Figure 4 is a perspective view from the front and one side.

I claim:

The ornamental design for a fishing reel, as shown.

LOUIS S. ELSINGER.
